UNITED STATES PATENT OFFICE.

WILLIAM H. SMYTH, OF BERKELEY, CALIFORNIA, ASSIGNOR TO HUMPHREY GAS PUMP COMPANY, A CORPORATION OF NEW YORK.

UTILIZING HEAT ENERGY.

1,089,681.

Specification of Letters Patent. Patented Mar. 10, 1914.

Application filed August 4, 1903, Serial No. 168,233. Renewed June 7, 1913. Serial No. 772,424.

To all whom it may concern:

Be it known that I, WILLIAM H. SMYTH, citizen of the United States, residing at Berkeley, in the county of Alameda and 5 State of California, have invented certain new and useful Improvements in Utilizing Heat Energy; and I do hereby declare the following to be a full, clear, and exact description of the same.

10 This invention relates to the art and means of utilizing heat energy.

Though the laws and principles governing the economical transformation of heat energy into a form more available for effective work are well known and fully appreciated by physicists and mechanics, the intensely destructive and excessively fugitive nature of the element involved, has heretofore rendered insurmountable the practical 20 difficulties of the problem. Thus the internally fired engine which represents the highest expression of the art, returns in useful work seldom more than 15% of the fuel heat value in good average present practice. 25 This wastefulness arises out of errors both in principle and design. In other words departures from the natural laws and principles which all agree must underlie the mechanical expression of the theoretical or 30 ideal heat motor.

So wide and obvious is the departure from correct principles in modern practice that even in theory the internally fired engine neither attempts nor aims to utilize the 35 whole of the fuel heat. On the contrary provision is made to uselessly dissipate seven-tenths or more of the heat generated in the cylinder. Two essentials to the law of operation of the typical internally fired engine, the exhaust and the water-jacket cost 40 in the neighborhood of 75% of all the fuel heat generated.

The object of the present invention is to utilize and transform into work the whole 45 of the energy generated by the combustion of the fuel, and as a secondary object to at least save the loss incident to the water-jacket and exhaust by so arranging the device that these costly provisions may be dispensed with.

Authorities agree that for the economical conversion of heat energy into work it is essential to provide:—1st. High initial temperature. 2nd. Low terminal temperature. 3rd. Minimum contact between hot 55

gases and cold walls. Stated in terms of ordinary practice these requirements would be:—1st. High compression. 2nd. Great expansion. 3rd. (a) Cylinder alternately as hot as inflaming gases and as cool as explosive charge, or (b) extreme piston velocity, or (c) compromise between (a) and (b). That the possible satisfaction of these requirements has reached a practical limit in the modern high speed internally fired 60 engine is easily demonstrable and that little, if any, improvement is to be anticipated along the lines of present practice.

The imperfections and limitations are the outgrowth and result of the mechanical 70 character of the transforming and storing means employed. These means are so inconsistent and out of harmony with the conditions and desired object as to suggest an impossibility that they should ever have 75 been contemplated as the logical mechanical satisfaction of the conditions of the problem involved in the internally fired engine.

The crank-connecting-rod and fly-wheel, notwithstanding its universal adoption 80 never has borne any rational relation to the problem in its customary association. It is simply an illogical and accidental left over from steam engine practice.

Owing to its nature, the crank-connecting-rod and fly-wheel precludes the necessary high piston speed at the very time in the cycle when it is most essential. No matter how high the rotative speed of the crank, the linear motion of the piston at the 90 time of ignition must necessarily be slow. This constitutes one of the disqualifications of this mechanism. Another and equally serious one is that the crank-motion limits the available expansion to the original atmospheric volume of the charge regardless 95 of its pressure. It thus makes the exhausting of the still inflaming gases a practical necessity. Again as it restricts the initial and terminal range to destructively high 100 temperatures, the wasteful water-jacket becomes unavoidable.

The crank-connecting-rod and fly-wheel, as a transformer of reciprocating into rotary motion, is all that could be wished, as 105 a converter of heat into work it is any thing but that. As a modifier of molar motion it is appropriate and economical, as a converter of molecular into molar motion it is costly and wasteful. No better or more con- 110

clusive evidence of this is required than the amazing difference which exists between the mechanical efficiency and the theoretical thermal efficiency in internal combustion engines. As a machine, the gas engine is practically perfect—as a heat motor *i. e.* a device for converting heat or heat energy into available or useful work, it is raw, crude and illogical to the last degree.

10 Further objects of the present invention are to avoid the stated difficulties and provide conditions and constructions in accordance with the correct theory of an economical heat motor in those respects in which 15 present practice departs therefrom. In the accomplishment of these objects the present invention differs from present practice in the following radical particulars:—1st. Expansion instead of being mechanically limited to atmospheric changes regardless of cylinder pressure, is practically unlimited and always extends to many volumes in excess of the original atmospheric volume of the charge. 2nd. The terminal temperature 20 instead of being that of flame is never more than atmosphere. 3rd. The heat dissipating water jacket is avoided and replaced by non-conductor of heat. 4th. Atmospheric back pressure is neutralized and avoided. 30 5th. The mechanically limited piston speed is replaced by unlimited velocity. 6th. The flaming exhaust is avoided by the practical absence of all exhaust.

Notwithstanding the radical and revolutionary character of the present invention its objects are mainly accomplished, as just suggested, by the simple expedient of discarding from the ordinary internally fired engine those improper and redundant parts 40 to the presence of which is due its inefficiency as a heat motor.

The accompanying drawings show characteristic forms of this invention which with the description herein will enable skilled mechanics to make and use the invention not only in the forms illustrated, but in the multitudinous modifications by which it may be adapted to the varying conditions of operation.

50 Referring to the drawings:—Figure 1 is a side elevation partly in section. Fig. 2 is a vertical section of a modified detail, on an enlarged scale. Fig. 3 is a plan section of a detail also on an enlarged scale. Fig. 55 4 is an elevation of a vertical single acting form partly in section.

In general terms this invention may be described as comprising a cylinder and a free, independent or projectile piston therein, 60 means for introducing, compressing and igniting explosive charges and an inclosed resilient cushion against which the charge expends its energy. This generic conception is carried out with some elaboration of detail in the accompanying drawings to

which reference will be made in the fuller description which follows.

1 is a cylinder preferably of considerable length compared with its diameter. It is closed at both ends with the exception of 70 valved passages or apertures to which more particular reference will later be made. These ends form charge chambers or expansion chambers. As the device may be either single or double acting and as in the latter 75 case both ends are substantially alike, the description of one end will suffice, it being understood that the description applies to either end. In the cylinder is a free, independent or projectile piston 2. An air 80 chamber 3 is provided, which for convenience is shown as integral with and surrounding the cylinder 1. A passage 4 controlled by a valve 5 connects the air chamber and cylinder. The air chamber is also 85 provided with an outlet pipe 6. There is also provided another aperture or passage 7 from the cylinder, this one however communicates with the exterior and is controlled by a valve 8. Both of the valve controlled 90 passages 4 and 7, though for simplicity of illustration shown as single apertures, may be multiplied.

Means for introducing suitable fuel are provided, shown in the present instance as 95 a gas pump consisting of a plunger 9 fitting cylinder 10; a valve block 11 is seated snugly in an enlarged extension bore of cylinder 10 and carries a fuel inlet valve 12. In the enlarged bore is also a buffer spring 13 resting between the valve block 11 and a plug 14 adjustably secured in the outer end of the enlarged bore. The pump cylinder 10 is adjustably secured to the end of cylinder 1 in any suitable manner as shown in 101 Fig. 1 or Fig. 4. A fuel inlet 15 is provided and passages 16 for the fuel between the interior of cylinder 10 and cylinder 1.

An igniting device is provided shown for the purpose of this disclosure as an ordinary wiping sparkler consisting of a spring electrode 17 attached to the plunger 9 and an adjustable insulated contact 18 and a source of electrical energy to which the electrodes are connected as diagrammatically indicated at 19.

110 A starting device is provided which may consist as shown in Fig. 1 and Fig. 3 of a rock shaft 20 projecting through the side wall of the cylinder having on its inner 120 end a tappet or finger 21 adapted to engage with piston 9 and on its outer end a suitable operating handle 22. The device may also be started by compressed air from chamber 3.

120 In Fig. 2 is illustrated a modification of valve 5 and its immediate surroundings, the purpose of which will be later described. This modification consists in providing a pocket or small chamber A cut off from both 125

the cylinder 1 and air chamber 3 but into which a portion of valve 5 projects. This pocket has a passage B of considerable area between it and cylinder 1 normally closed by inwardly opening valve b. There is also a second passage C of very much smaller area, the entrance area of which is made variable by suitable means shown as a needle valve D. To start this device the handle 22 is depressed causing the tappet to drive the piston 9 inward and the gas pump to perform its functions whereby a volume of gas or other suitable fuel is introduced into cylinder 1. This motion also effects 10 sparking contact between the electrodes and thus produces an explosion. The piston is thus driven to the opposite end of the cylinder where it engages with the corresponding gas pump &c., and the operation becomes 15 continuous.

The machine being in operation the following cycle is repeated indefinitely:—The explosive expansion of the ignited charge starts the piston instantly and with a velocity commensurate to the explosive energy expended, as the charge has but to overcome the inertia of the free piston unhampered by a rod passing through a gland or any mechanical attachment. The piston in consequence of its projectile character, stores up in the form of momentum all of the energy exerted upon it less only the fractional percent. lost by friction. When the piston has reached a position in its travel where the 25 charge gases have expanded to below atmospheric pressure, the valve 8 opens by atmospheric pressure and air rushes in, this prevents a vacuum forming and neutralizes the otherwise unbalanced atmospheric pressure.

Owing to its stored up energy the projectile piston continues with great velocity compressing the air in front of it till the pressure in front of the piston in cylinder 1 30 is greater than that in the air chamber. At this point the valve 5 in front of the piston opens and the compressed air passes into the air chamber. This continues till the piston has passed valve 5 when it meets 35 with the increasing pressure of the confined air to which it transfers its remaining energy.

During the last part of its travel the piston 2 has encountered the buffer piston 9 40 and driven the gas out of cylinder 10 into the confined and compressed air in front of the piston 2 and sparked the thus formed explosive mixture. Whatever remnant of energy may remain in piston 2 is absorbed 45 and stored by buffer spring 13. The cycle thus complete will repeat indefinitely. Each end though performing its own functions coöperates with the other making together a double acting transformer of heat energy.

The adjustable character of the attachment of cylinder 10, the electrode 18 and buffer spring 13 provide for sparking at the proper time and also against shock in the final stopping of the piston by permitting 50 of longer travel of piston and consequently greater compression of the charge.

Under most conditions, proper proportioning of the parts will provide against opening of valve 5 by direct pressure of 55 the expanding charge, though should this happen it would not materially affect the operation of the device. When however it is deemed advisable to prevent this occurring, the modification on Fig. 2 may be adopted. With this construction chamber A will be charged at each explosion with the initial pressure. This high pressure exerted on sufficient preparation of the back of valve 5 added to the normal pressure of chamber 60 5 upon the enlarged surface of the back of the valve will more than counterbalance the direct pressure upon the front of valve 5. The pressure existing in cylinder 1 when valve 5 is uncovered by the passing piston 65 is of course much less than the initial pressure, on account of the expansion of the gases permitted by the travel of the piston. The passage C is a bleeder to relieve chamber A and valve 5 of the excess of pressure 70 by the time the piston returns on its back journey. The modification Fig. 2 or an equivalent device may be employed when not directly necessary as a simple precautionary construction.

Though I deem the double acting form 75 preferable as giving practically double power for substantially the same weight of material, the device is not of necessity so constructed.

Not only is the device operative with one end thrown entirely out of operation but it may with good economy be designed to work in this manner as shown in Fig. 4. This form is shown as being mounted vertically to illustrate that the position of the device does not in any essential manner affect its working. In this form the upper part of the cylinder 1 becomes and performs the functions of a resilient cushion to take up and return the impact energy of the piston. It may be provided with a cock or valve E to renew or control the volume of air in cylinder 1 above the piston 2.

It will be observed that by arranging the valve 8 to open freely in response to atmospheric pressure, the unproductive work which would otherwise have to be expended in lifting or displacing the atmosphere is converted into productive work. In other words, when the pressure of the expanding gases falls below atmospheric pressure upon the opposite side of the piston it permits the remaining and corresponding explosive energy to be profitably exerted. This per-

cular effect apart from the many other novel features in this disclosure, is wholly new and does not appear in any form in this or any other art with the exception of the devices forming the subject matter of my co-pending applications which it also characterizes. In further explanation it may be stated that as this method of utilizing heat energy, owing to the projectile character of the piston, provides for expansions unlimited mechanically, that is to say unlimited except by the resistance to be overcome *i. e.* useful work, the expansion will usually extend far beyond that degree which would reduce the pressure below atmospheric pressure, but expansion below atmosphere would be resisted by the thus unbalanced atmospheric pressure and in effect add the difference in pressure to the work which the expanding gases are performing. If therefore at the instant at which the pressure of expansion falls below that of atmosphere, the atmospheric pressure is permitted entrance to supplement the wan ing pressure due to heat, it neutralizes the retarding effect of atmospheric pressure. That is to say atmospheric pressure balances atmospheric pressure and the full effect of heat energy is thus permitted to be applied usefully so far as concerns retardation by atmospheric pressure. This differs essentially from the method of utilizing vacuum as exemplified in the steam engine and other vacuum devices. Under the conditions of the present invention, atmospheric pressure is applied inside instead of outside, so to speak. It is applied to a piston already in motion the static inertia of which has been overcome by energy acting in the same direction. This difference is an important one from the practical and commercial point of view. As illustrated in the present invention the pressure of the expanding gases and that of atmosphere are united in a single continuous effect with consequent simplification in an economy of controlling mechanisms and this in addition to considerations of thermal efficiency.

It will be seen from the foregoing that notwithstanding the radical nature of the departure from present practice involved in this disclosure, there is no mechanism therein necessary for the complete carrying into effect the invention or inventions described, which requires other than the ordinary knowledge of mechanics skilled in gas engine practice. Such mechanics also will be enabled from the disclosure by means of their skill and knowledge to modify the form, location, construction, proportion, &c. of the various parts even to the extent of altering radically the appearance, without departing from the essential nature of the invention. Such changes will inevitably be made to meet the ideas of designers and constructors

and also to adapt it to the various requirements of location and operation. Some of these changes may and doubtless will carry into effect some of the objects of the invention in a more satisfactory manner than the forms herein used as illustration. These forms are not supposed to be the best possible, either in design or construction, but are simply preferred forms for ordinary general use and which best serve the present purpose.

As illustrated the facility with which the invention herein described lends itself to change and modification of form and construction, some such differences are shown in the various figures. For example the pipe F with its valve f which forms a controllable communication between the compressed air chamber 3 and the cylinder 1 may be employed as a starting device alone or in connection with the starting handle 22. It will be seen that by this means if there be compressed air in the chamber 3, by opening the valve f at the appropriate end of the cylinder, the piston may be driven to the opposite end and so effect the starting.

In the form illustrated in Fig. 4, the gravity of the projectile piston itself with or without the starting appliances illustrated in Fig. 1 assists in the starting of the device. In this latter figure also is illustrated the arrangement both of air inlet and outlet valve 8 and 5 respectively in which a multiplicity of such valves is provided for. These valves may be arranged in circular groups or otherwise as circumstances or the form of the machine may indicate. Again in Fig. 4, the contact and buffer spring arrangement is shown in a manner which avoids metallic springs by substituting air cushions. For buffer spring 13 is substituted air, the plate 11 forming a piston snugly fitted into the enlarged extension of cylinder 10. A hollow rod G connected to the plate 11 forms a gas inlet. A pipe H with a valve h controllably communicates either with the outside atmospheric air or with air chamber 3 so that any desired resistance may be offered to the piston 2.

The means for adjusting the volume of the charge or its compression by increasing or diminishing the cubical contents of the cylinder 1 between the outlet valve 5 and the cylinder end is also in this figure shown as consisting of a slid able connection between the end of cylinder 1 and the remainder of the cylinder with adjusting screws I provided for this purpose. The means also for providing for the contact between the pump plunger 9 and piston 2 is shown in Fig. 4 to be modified from a tail piece projecting from the piston 2 to a socket J recessed into the piston. It thus forms an air cushion or buffer between plunger 9 and piston 2.

No specific igniting device is shown in

Fig. 4, and this is omitted for the purpose of illustrating the fact that under suitable conditions, the igniting device may be omitted or at least thrown out of operation and the device permitted to perform the igniting function by high compression of the charge.

In view therefore of the radical nature of this invention and the facility with which practically each one of its mechanical elements may be changed and modified, I do not desire to confine myself in any of the above particulars or in fact to any particular material expression of this invention.

What I claim is:

15 1. An internal combustion engine comprising a cylinder with an independent piston, a charge chamber attached to the cylinder provided with a pump suitably placed to engage the piston and be operated thereby 20 and introduce fuel into the cylinder, means for commingling a volume of air with the fuel to form an explosive charge in the cylinder, an igniter operated by the piston, the cylinder and piston being suitably arranged 25 to compress the charge by the momentum of the independent piston, a resilient cushion against which the charge partially expends its energy and a buffer in addition to the resilient cushion to arrest the piston.

30 2. An internal combustion engine comprising a cylinder with an independent piston, a charge chamber attached to the cylinder provided with a pump suitably placed to engage the piston and be operated thereby to 35 introduce fuel, means for commingling a volume of air with the fuel to form an explosive charge in the cylinder, an igniter operated by the piston, the cylinder and piston being suitably arranged to compress 40 the charge by the momentum of the piston, a resilient cushion against which the charge partially expends its energy, a buffer to absorb the remaining energy and arrest the piston, and an air chamber surrounding and 45 communicating with the cylinder by a valve controlled passage.

3. A device for utilizing heat energy comprising a cylinder and a free metallic piston therein, a charge chamber attached to the 50 cylinder provided with a pump operated by the piston adapted to introduce fluid fuel, means for commingling a volume of air with the fuel to form an explosive charge, an igniter operated by the piston, means adapted 55 to form a resilient cushion against which the charge expends its energy, and an air chamber surrounding the cylinder.

4. A device for utilizing heat energy comprising a cylinder and a free metallic piston 60 therein, a charge chamber attached to the cylinder provided with a pump operated by the piston adapted to introduce fluid fuel, means for commingling a volume of air with the fuel to form an explosive charge, an igniter operated by the piston, the piston be-

ing suitably arranged to compress the charge by its momentum, a resilient cushion against which the charge partially expends its energy and a buffer in addition to the resilient cushion adapted to arrest the forward motion of the piston and an air chamber surrounding and communicating with the cylinder by a valve controlled passage.

5. In a device of the character described, the combination of a cylinder having an expansion chamber at the end thereof, a piston adapted to reciprocate in said cylinder, a valve controlled air intake connected with the expansion chamber, means for introducing combustible gas into the expansion chamber, said means controlled by the piston whereby the gas is mixed with the air in the expansion chamber, and the mixture compressed by the movement of the piston, and means for igniting the mixture.

6. In a device of the character described, the combination of a cylinder having an expansion chamber at the end thereof, a piston adapted to reciprocate in the cylinder, a valve controlled air intake connected with the expansion chamber, means for introducing combustible gas into the expansion chamber, said means controlled by the piston whereby the gas is mixed with the air trapped in the expansion chamber and the mixture compressed by the movement of the piston, and piston-controlled means for igniting the mixture.

7. In a device of the character described, the combination of a cylinder having an expansion chamber at the end thereof, a piston adapted to reciprocate in the cylinder, a valve controlled air intake connected with the expansion chamber, means for introducing combustible gas into the expansion chamber, said means controlled by the piston whereby the gas is mixed with the air in the expansion chamber and the mixture compressed by the movement of the piston, means for igniting the mixture, and manually operative means for arbitrarily actuating the gas introducing means and the igniting means.

8. In a device of the character described, the combination of a cylinder having an expansion chamber at the end thereof, an air chamber having valve controlled connection with the cylinder, a free piston adapted to reciprocate in said cylinder, a valve controlled air intake connected with the expansion chamber, means for introducing combustible gas into the expansion chamber, said means actuated by the piston whereby the gas is mixed with the air trapped in the expansion chamber, and the mixture compressed by the momentum of the piston, and means for igniting the mixture.

9. In a device of the character described, the combination of a cylinder having expansion chambers at the ends thereof, an air
